[57] CLAIM

The ornamental design for an advertising display board and business card holders therefor, as shown and described.

DESCRIPTION

FIG. 1 is a perspective view of an advertising display board and business card holders therefor showing my new design;

FIG. 2 is a front elevational view thereof, the rear side being plain and unornamented;

FIG. 3 is a top plan view thereof;

FIG. 4 is a bottom plan view thereof;

FIG. 5 is a right side elevational view thereof, the left side being a mirror image;

FIG. 6 is an enlarged vertical section view thereof.
